UNITED STATES PATENT OFFICE.

CHARLES THOMAS PHIPPS, OF SALTVILLE, VIRGINIA.

THROTTLE-OPERATING MECHANISM FOR LOCOMOTIVES.

Application filed May 22, 1922. Serial No. 562,815.

To all whom it may concern:

Be it known that I, CHARLES THOMAS PHIPPS, a citizen of the United States, residing at Saltville, in the county of Smyth

5 and State of Virginia, have invented certain new and useful Improvements in Throttle-Operating Mechanisms for Locomotives, of which the following is a specification, reference being had to the accompanying drawings.

10 This invention relates to locomotives or other apparatus having throttle valves, and particularly to mechanism for operating the throttle valves thereof.

15 In a locomotive the throttle valve is operated by a rod disposed within the locomotive boiler and operatively connected to the throttle valve, which in turn is disposed within the steam dome of the boiler, and this

20 throttle rod must, of necessity, extend out through one end of the boiler and through the boiler sheet in order that it may be connected to operating means convenient to the engineer. Ordinarily, one or more packing

25 glands are used through which the operating rod extends and whenever it is necessary to re-pack these glands the boiler has to be blown off. Inasmuch as it takes two or

30 three tons of coal to get steam on a boiler, it is obvious that the blowing off of this steam in order to re-pack the throttle valve rod is relatively costly.

The general object of my invention is to provide a mounting for the operating rod of 35 the throttle valve which shall not involve the use of any packing and, therefore, not involve the renewal of the packing.

A further object is to provide a construction of this character which is of such character that all wear due to the operation of the throttle valve actuating mechanism is taken up and which at all times remains tight and prevents any loss of time on the throttle operating rod or shaft.

45 Other objects will appear in the course of the following description.

My invention is illustrated in the accompanying drawings, wherein:—

Figure 1 is a top plan view of a portion 50 of a locomotive with my device applied thereto;

Figure 2 is a longitudinal sectional view of the locomotive and my improved throttle valve mechanism, the top of the dome being omitted;

Figure 3 is an enlarged sectional view through the throttle valve actuating mechanism.

Referring to these drawings, A designates the usual boiler of a locomotive and B the dry pipe thereof. Coacting with this dry pipe is the usual throttle valve C. This is carried by a bell crank lever D, in turn connected by a rod E to the throttle valve actuating mechanism. So far I have illustrated 60 and described an ordinary throttle valve disposed in the usual steam dome.

For the purpose of reciprocating the rod E to close or open the throttle valve, I provide a vertical shaft or rod 10 which extends downward through the two horizontally disposed webs 11 mounted in a dome or annular portion 12 at the rear end of the boiler, this shaft carrying at its upper end the lever 13 and at its lower end within the 70 boiler having applied thereto the arm 14 which is pivotally or otherwise connected to the rod E. The webs 11 are apertured, as at 15, the walls of these apertures being upwardly beveled, and mounted upon the shaft 10 and rotatable therewith are the conical bearing members 16 which have ground faces and have a steam-tight engagement with the ground faces of the walls defining the openings 15.

Surrounding the shaft 10 and bearing at its lower end against the upper web 11 and bearing at its upper end against the lever 13 is a coiled spring 17 under compression.

This spring bearing at its lower end against the upper web 11 urges the shaft 10 upward and, therefore, urges the conical bearing members 16 into close engagement with the apertures through the webs 11. Inasmuch as these apertures have ground seats for 80

90 these conical bearing members, it is obvious that all wear will be taken up by the upward pressure of the spring and that as fast as the seats 15 wear, the corresponding conical members will be forced upward by the 95

100 spring so that the apertures through which the shaft 10 passes will be at all times closed against escaping steam and that there will be no necessity of renewing any packing during the life of the members 16. Thus 105

there will be no necessity of discharging the steam from the boiler in order to re-pack the glands through which the throttle operating rod passes, but that this throttle operating rod will be properly kept in a steam- 110

tight engagement with the boiler for a very long time without any necessity of renewing the bearing members 16.

I have illustrated two webs 11, but it will be understood that any number of webs may be used. The purpose of using a plurality of webs is to more positively prevent leakage of steam. The conical bearing members 16 may be made of bronze, brass, steel or any other desired material. The same material may be used for the webs 11. These members 16 may be formed upon the shaft which carries the members or be separately formed and applied to the shaft. While I have illustrated a lever-like handle whereby the shaft carrying the conical bearing members may be operated, I do not wish to be limited to this as it is obvious that any other desired means might be used for operating this shaft 10.

It will be obvious that changes might be made in the detailed construction and arrangement of parts and the material from which the parts are made without departing from the spirit of the invention.

I claim:

1. A locomotive boiler having an annular member attached to the locomotive wall, a plurality of webs crossing said annular member, said webs being apertured, a throttle valve disposed in the boiler, an operating rod therefor within the boiler, and an actuating shaft for the rod operatively connect-

ed thereto and extending through the apertures in said webs and provided with means at its outer end whereby it may be oscillated, a pair of conical bearing members carried upon said shaft and fitting the apertures in said webs, and a spring urging said shaft outward and the bearing members into engagement with the walls of the apertures, the contacting faces of the walls of the apertures and the conical bearing members being ground.

2. A locomotive boiler having at its rear end an upwardly projecting, annular portion surrounding the opening through the boiler wall, a plurality of webs crossing said annular portion, said webs being apertured, a throttle valve disposed in the boiler, an operating rod therefor, and an actuating shaft for the rod operatively connected thereto and extending through the apertures in said webs and provided with a handle at its outer end, a pair of conical bearing members carried upon said shaft and fitting the apertures in said webs, and a spring urging said shaft outward and the bearing members into engagement with the walls of the apertures, the contacting faces of the walls of the apertures and the conical bearing members being ground.

In testimony whereof I hereunto affix my signature.

CHAS. THOMAS PHIPPS.
